UNITED STATES PATENT OFFICE.

ANNA L. GACOND, OF WASHINGTON, DISTRICT OF COLUMBIA,

CLEANING COMPOUND.

No Drawing.

Application filed May 7, 1925. Serial No. 28,737.

To all whom it may concern:

Be it known that I, ANNA L. GACOND, a citizen of the United States, residing at Washington, District of Columbia, have invented certain new and useful Improvements in Cleaning Compounds, of which the following is a specification.

This invention appertains to a compound for cleaning and polishing purposes and the primary object of the invention is to provide a detergent, which will effectively clean and polish metallic, vitreous and enameled objects and at the same time act as a disinfectant therefor.

15 A further object of the invention is to provide a soft soap compound for use as a general household cleaning detergent, on paint, metal, and glass articles and which owing to its antiseptic qualities is especially adapted for cleaning toilet bowls, wash tubs, kitchen sinks and the like.

20 A further object of the invention is to provide a soft soap compound for general house cleaning purposes, which will be easy to manufacture and which can be placed upon the market at a reasonable cost.

25 The composition preferably consists of a mixture of soap, feldspar, creolin, ammonia and water. The feldspar is preferably in the nature of a finely ground rock, while

the soap can be of any kind, such as laundry soap containing naphtha. The creolin is a product taken from coal tar.

35 In preparing the composition the ingredients are used in about the following proportions: Soap 2 lbs., feldspar 2 lbs., creolin $\frac{1}{2}$ ounce, common household ammonia 2 ounces, and water 8 pints.

40 The soap is cut up into fine particles and added to the water which is allowed to boil until all of the soap is dissolved. The feldspar, ammonia and creolin is then added to the mixture and the mixture is thoroughly agitated and allowed to boil for about fifteen minutes. The mixture is then allowed 45 to cool and is ready for use.

45 The composition is preferably applied with a wet cloth which is dipped into the soap and applied to the object to be cleaned. The object is rubbed lightly with the cloth 50 after which the same cloth is used and the article is rinsed with warm water.

What I claim as new is:

55 A cleaning paste embodying water eight pints, soap two pounds, feldspar two pounds, creolin a half ounce and household ammonia two ounces.

In testimony whereof I affix my signature.

ANNA L. GACOND.
